UNITED STATES PATENT OFFICE.

ARTHUR C. HAYDEN, OF BROCKTON, MASSACHUSETTS.

HONER AND STROPPER.

1,073,119.

Specification of Letters Patent. Patented Sept. 16, 1913.

Application filed October 26, 1911. Serial No. 656,874.

To all whom it may concern:

Be it known that I, ARTHUR C. HAYDEN, a citizen of the United States, and resident of Brockton, county of Plymouth, State of Massachusetts, have invented an Improvement in Honers and Stroppers, of which the following description, in connection with the accompanying drawings, is a specification, like letters on the drawings representing like parts.

This invention relates to devices for sharpening razors and the like, particularly the short blades used in the various types of safety razors.

The invention is an improvement in a type of such devices lately devised by me for effecting a relative movement of the blade to be sharpened, to the sharpening element so that the blade is pressed against the sharpening element for either drawing strokes for stropping, or thrusting strokes for honing, as desired; there being preferably provision for readily changing the sharpening element so that the operative surface presented to the blade is in the nature of a stone for honing, and of leather or the like for stropping.

The special objects of the present invention are to provide simple positive geared connections for causing the blade to be pressed against the surface of the sharpening element during the operative movement and in connection therewith a simple easily controlled and durable means for effecting reversal of the direction of operative impulse whereby the blade is pressed against the sharpening element for either drawing or thrusting strokes on either direction of movement, according to the way said reversing means is set.

The invention will be better understood from the following detailed description, taken in connection with the accompanying drawings and will be thereafter pointed out in the appended claims.

Referring to the drawings, Figure 1 is a side elevation of a device constructed in accordance with my invention; Fig. 2 is a plan view thereof; Fig. 3 is a detail side view of the reversing device; Fig. 4 is a detail section on line 4-4 of Fig. 3; Fig. 5 is a detail section through the friction slip connection; Fig. 6 is a detail of a modified form of the friction slip connection; and Fig. 7 is a detail of a further modified form of such connection.

The framework of the device consists in stout rods 1 held in parallel spaced apart relation by having their ends rigidly clamped to plates or bars 2 by means of nuts 3, the plates 2 having holes fitted over reduced extremities of the rods 1 on which the nuts 3 are engaged. The rods 1 constitute slide-ways upon which a carriage 4 is adapted to slide, this carriage being preferably formed as a metal stamping, and having spaced apart upturned ears 5 at either side with apertures therein engaging the rods 1. In the illustrative embodiment of the invention shown the blade holder is mounted on the movable carriage 4, and the sharpening element is mounted on the fixed framework, but the invention is not limited in this respect, since this relation of parts may be reversed without departing from the spirit of the invention in its broader aspect. The sharpening element is shown at 6 reversibly and adjustably mounted on a bed support 7 fixed to bars 8, 9 extending lengthwise of the framework and fixed to the end bars 2. This sharpening element 6 is preferably provided with a stone surface on one side for honing, and with a surface of leather or the like on the other side for stropping, there being an intermediate metallic plate provided with opposite central lugs 10 fitted between upstanding ears 11 struck up from the bed 7, and other opposite lugs 12 adjacent its ends adapted to cooperate with screws for adjustment of the sharpening element. The sharpening element can thus be instantly removed and set in place with its other side up so as to change the operative surface from a stropping to a honing one, or vice versa. The slide carriage 4 is provided with upstanding ears 13, 14 at its opposite sides furnishing journal bearings for a shaft 15 to which the blade holder 16 is secured. This holder consists, as shown, of bars or plates 17, 18 extending at either side of the shaft 15 with loop springs 19 adapted to press the inwardly extending portions of the plates upon a blade *a* to be sharpened. These plates are provided with finger clips 20 adapted to open the same to remove or insert a blade, as desired. The shaft 15 has an arm 21 fixed thereto at one end and the plates 17, 18 have lugs 22 engaging this arm at either side so as to be made to partake of the oscillation of the shaft. The arm 21 also cooperates with cam projections 23 extending upward at either side of the bed

7 for controlling the oscillatory movement of the blade and insuring its proper presentation to the sharpening element, as later more fully explained.

5 The blade holder is preferably oscillated so as to bring it into operative relation to the sharpening element on successive strokes, and in the illustrative form of the invention shown I provide means whereby 10 this oscillation, and also the pressing of the blade against the sharpening element during the operative movements, is effected from the reciprocation of the carriage. To this end the lengthwise extending bar 9 has 15 its upper edge formed as a rack 24 and the teeth thereof are engaged by the teeth of a pinion 25 mounted on a plate carrier 26 which swings about an axis 27 on a lateral extension 28 of the ear 14. The swinging plate 26 also carries a pinion 29 in mesh with the pinion 25 and the plate 26 is so mounted that one of these pinions, but not both at the same time, is adapted to be engaged with a pinion 30 on shaft 15, according 20 to which way the plate 26 is shifted, the pinion 25 remaining in mesh with the rack 24 in either position of the plate. This shifting pinion carrier is provided with a handle 31 for convenient operation and it 25 will usually stay in either shifted position without any special holding means. To insure that the plate shall be shifted to just the right extent for either position and that it remain in such position, however, locking means may be provided, and for this 30 purpose the plate 26 is provided with spaced apart holes 32, 33 adapted to be engaged by a locking pin 34 carried by a spring plate 35 fixed at 36 to the ear 14, this pin 34 passing through and being guided in a hole 37 of the lateral extension 28. The pinion 30 is 35 loosely mounted on the shaft 15 and is held clamped between plates 38, 39 fixed to the shaft with an interposed friction washer 40 40 of leather or the like. These plates 38, 39 are fixed to the shaft in such adjustment that the pinion 30 held therebetween imparts through the friction disk 40 just enough impulse to press the blade against 45 the sharpening element with the proper amount of force for best results in use, after oscillating the blade to bring it to operative position in either direction. This adjustment for best results is usually most 50 readily and accurately determined at the factory and does not require to be changed through a long period of use. In order to provide for adjustments of the friction impulse imparted to the blade, should these 55 be desired however, an adjusting means such as shown in either Figs. 6 or 7 may be incorporated.

As seen in Fig. 6, the plate 39', instead of being fixedly secured to the shaft 13, is 60 slidable thereon and is adapted to be ad-

justably pressed against the pinion 30 by a knurled nut 41 engaged with a threaded portion 42 of the shaft 15', there being a lock nut 43 coöperative with nut 41 to hold the same against displacement.

In Fig. 7 the plate 39'' is slidable on shaft 15'' and is pressed against the pinion 30 by a spring 44, the tension of this spring being adjustable by having a backing against the nut 45 threaded in the ear 14, 75 this nut having a central bearing aperture 46 for the plate holder shaft 15''.

The framework of the device is provided with a suitable handle 47 which may be detachably threaded to one of the bars 2 centrally thereof and the carriage 4 preferably has a similar detachable handle 48 engaged centrally of the bottom thereof.

In use, the sharpening element is set in the bed 7 so as to present a honing or stropping surface as required, and the handle 31 is moved so as to bring either the pinion 25 or 29 into engagement with the pinion 30. As shown in Fig. 1, with the pinion 25 engaged with pinion 30 the parts are connected so that the blade is pressed against the sharpening element as it is drawn thereover, *i. e.* it is in position for stropping. For this operation the arm 21 coöperates with the cam projections 23 to compel the 80 movement of the blade holder down through the frame as the carriage starts in either direction, bringing it up to position for a drawing movement over the sharpening element and releasing it so that it may be 85 pressed against the sharpening element just as it comes over the same. As the handle 31 is shifted to bring the pinion 29 into mesh with pinion 30 the device is connected for 90 pressing the blade against the sharpening element on the thrusting strokes and in this 95 operation the arm 21 coöperates with the cam projections 23 to prevent premature engagement of the blade with the sharpening element, *i. e.* the blade is held by the 100 arm 21 riding over the cams 23 up above the plane of the sharpening element surface 105 until the blade edge is started over such surface, whereby the blade is prevented from premature turning down and chipping into 110 the lateral edges of the hone.

It is thus to be noted that the operative connections between the framework and the blade holder, for causing the oscillation of the blade and the pressing thereof against 115 the sharpening element on the operative strokes, are of a simple direct-drive character not liable to get out of order and adapted for long use without deterioration by wear. Likewise, that the device is capable 120 of a practically instantaneous change from a honer to a stropper or vice versa, and that to effect this no manipulation is required 125 which could be wrongly performed even by the most careless or inexperienced.

The structural details may be widely varied without departing from the spirit of the invention, and I therefore do not desire to be limited as to these by the illustrative embodiment herein shown or in any way except as set forth in the appended claims.

Having described my invention, what I claim as new and desire to secure by Letters Patent is:

1. A combination stropper and honer, comprising a frame, a carriage slidable thereon, operative elements consisting in a blade holder and a sharpening device, one mounted on said frame and the other on said carriage, and geared connections between the frame and one of said operative elements for causing a blade in said blade holder to be pressed against the sharpening device at each reciprocation, said geared connections having permanently associated therewith a reversible portion formed to be shiftable while remaining assembled with the device for causing the blade to be pressed against the sharpening element for either drawing or thrusting strokes at will.
2. A combination stropper and honer, comprising a frame, a carriage slidable thereon, operative elements consisting in a blade holder and a sharpening device, one mounted on the frame and the other on the carriage, and the blade holder having shifting movement to present a blade carried thereby to the sharpening device on successive strokes, and geared connections between the frame and the blade holder for shifting the blade holder and causing it to be pressed against the sharpening element, said connections having permanently associated therewith a shifting portion formed to be shiftable while remaining assembled with the device to cause the blade holder to be pressed against the sharpening device for either drawing or thrusting strokes at will.
3. A combination stropper and honer, comprising a frame, a carriage slidable thereon, operative elements consisting in a sharpening device and a blade holder, one mounted on the frame and the other on the carriage, said blade holder being mounted for oscillation to present a blade carried thereby to the sharpening device, and geared connections between the frame and the blade holder permanently associated therewith for causing the blade to be oscillated and pressed against the sharpening device, said connections having a direction changing element formed to be shiftable while remaining assembled with the device and a friction slip element co-operative to cause a blade in said holder to be yieldingly pressed against the sharpening device for either drawing or thrusting strokes at will.
4. A combination stropper and honer, comprising a frame, a carriage slidable
- thereon, operative elements consisting in a blade holder and a sharpening device, one mounted on the carriage and the other on the frame, the blade holder being mounted for shifting to present a blade therein to the sharpening device on movement in both directions and geared connections between the frame and the blade holder permanently associated therewith including gears formed to be shiftable while remaining assembled with the device adapted to transmit impulse to cause the blade holder to press a blade therein against the sharpening device for either drawing or thrusting strokes at will, and said connections including a friction slip adapted to cause a definite yielding pressure of the blade against the sharpening device.
5. A combination stropper and honer, comprising a frame, a carriage slidable thereon, operative elements consisting in a blade holder and a sharpening device, one mounted on the frame and the other on the carriage, the blade holder being mounted for oscillation, a rack fixed to the frame, and gears carried by the carriage in connection with said rack, said gears having a friction slip connection with the blade holder and being shiftable while remaining in permanently assembled relation to the device to transmit impulse thereto in either direction for causing the blade in the holder to be pressed against the sharpening device for either drawing or thrusting strokes at will.
6. A device of the kind described, comprising a frame, a carriage slidable thereon, operative elements consisting in a blade holder and a sharpening device, one mounted on the frame and the other on the carriage, the blade holder being mounted on a shaft for oscillation, a rack rigid with the sharpening device, and gears permanently associated with the blade holder having one thereof in mesh with said rack, said gears having a friction slip connection with the blade holder and certain thereof being shiftable while remaining in permanently assembled relation to the device to impart impulse in operative directions to the blade holder for the purpose stated.
7. A device of the kind described, comprising a frame, a carriage slidable thereon, a sharpening device mounted on the frame, a blade holder mounted for oscillation on the carriage, a rack fixed to the frame and extending lengthwise thereof, and shiftable reversing gears mounted on the carriage with a friction slip connection to the blade holder and a permanent geared connection with said rack, whereby a blade in said holder is caused to press against the sharpening device for either drawing or thrusting strokes at will.
8. A device of the kind described, comprising a frame, a carriage slidable thereon,

- a sharpening device mounted on the frame, a blade holder mounted for oscillation on the carriage, a rack fixed to the frame and extending lengthwise thereof, shiftable reversing gears mounted on the carriage with a friction slip connection to the blade holder and a permanent geared connection with said rack, whereby a blade in said holder is caused to press against the sharpening device for either drawing or thrusting strokes at will, and means for controlling the blade holder movement to cause proper presentation of the blade to the sharpening device for either drawing or thrusting strokes.
- 15 9. A device of the kind described, comprising a frame, a carriage slidable thereon, operative elements consisting in a blade holder and a sharpening device, one mounted on the frame and the other on the carriage, and one having a shifting movement for presentation to the other on movement in both directions, geared connections from the frame to said shiftable element in permanently assembled relation to the device having provision for causing a blade in the blade holder to be pressed against the sharpening device for either drawing or thrusting strokes at will, said connections having a friction slip element, and means for positively controlling the blade movement to prevent premature presentation of the blade to the sharpening device.
- 10 16. In testimony whereof, I have signed my name to this specification in the presence of two subscribing witnesses.
